(57) **CLAIM**

The ornamental design for a rear fascia reflector, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a rear fascia reflector showing our new design;

FIG. 2 is a front view thereof;

FIG. 3 is a rear view thereof;

FIG. 4 is a side view thereof;

FIG. 5 is top view thereof; and,

FIG. 6 is a bottom view thereof.

**1 Claim, 4 Drawing Sheets
(4 of 4 Drawing Sheet(s) Filed in Color)**

Related U.S. Application Data

a continuation-in-part of application No. 29/764,837, filed on Jan. 4, 2021, now Pat. No. Des. 953,932, and a continuation-in-part of application No. 29/764,840, filed on Jan. 4, 2021, now Pat. No. Des. 954,602.
